DESIGN FOR A CAKE OF SOAP

Gordon D. Voorhis, Rhinebeck, N. Y., assignor to
Voorhis-Tiebout Company, Inc., Rhinebeck,
N. Y., a corporation of New York

Application May 8, 1941, Serial No. 100,837

Term of patent 14 years

To all whom it may concern:

Be it known that I, Gordon D. Voorhis, a citizen of the United States and resident of Rhinebeck, in the county of Dutchess and State of New York, have invented a new, original, and ornamental Design for a Cake of Soap, of which the following is a specification, reference being had to the accompanying drawing, forming part thereof.

In the drawing:

The figure is a perspective view of a cake of soap, showing my new design.

The characteristic feature of my design resides in a rectangular cake of soap on one side of which are three uniformly spaced ribs, separated by a pair of grooves, said grooves being of substantially one-half the depth of the said cake of soap; and the top of the central rib lying in a plane beneath the side ribs, all as shown.

I claim:

The ornamental design for a cake of soap, as shown and described.

GORDON D. VOORHIS.
